UNITED STATES PATENT OFFICE.

HENRY ED DOWNER, OF PRINCETON, ILLINOIS.

COAL-CHUTE ATTACHMENT.

1,407,391.

Specification of Letters Patent. Patented Feb. 21, 1922.

Application filed September 9, 1921. Serial No. 499,511.

To all whom it may concern:

Be it known that HENRY E. DOWNER, citizen of the United States, residing at Princeton, in the county of Bureau and State 5 of Illinois, has invented certain new and useful Improvements in Coal-Chute Attachments, of which the following is a specification, reference being had therein to the accompanying drawings.

10 The invention relates to coal chute attachments and has for its object to provide a device of this character comprising a horizontally disposed platform on which the end of the coal chute is disposed, said platform 15 beyond the end of the coal chute being provided with a horizontally disposed segmentally shaped deflecting plate for deflecting the coal to either side of the platform, according to the position of the segmentally 20 shaped plate, thereby allowing the coal to be distributed in the cellar as desired.

A further object is to provide a vertically disposed frame adapted to be disposed beneath the inclined chute adjacent a window, 25 said frame having vertically disposed bars to the upper ends of which a chain is fastened, which chain engages under the coal chute and is held in engagement therewith by means of cables passing through blocks 30 supported on the chute, said cables passing through eyes adjacent the lower end of the frame. Also to support the horizontally disposed platform from the lower end of the frame and from a transversely disposed 35 member pivoted to the lower end of the frame, said platform being locked at various angles in relation to the frame by a notched brace.

With the above and other objects in view 40 the invention resides in the combination and arrangement of parts as hereinafter set forth, shown in the drawings, described, and claimed, it being understood that changes in the precise embodiment of the invention 45 may be made within the scope of what is claimed without departing from the spirit of the invention.

In the drawings:—

Figure 1 is a perspective view of the chute 50 attachment showing the same attached to a coal chute.

Figure 2 is a perspective view of the outer end of the horizontally disposed member, showing the segmentally shaped deflecting 55 member in reverse position to that shown in Figure 1.

Figure 3 is a detail sectional view through one of the uprights of the frame, showing the notched brace and means for locking said notched brace in adjusted position.

60

Referring to the drawings, the numeral 1 designates a cellar window, and 2 a coal chute extending downwardly and inwardly from said window. It has been found that ordinarily when coal is discharged into a 65 cellar through a chute, that the coal is deposited in one position, and that it becomes necessary for the operator to shovel the coal to the desired position on either side of the chute for proper distribution of the coal 70 within the cellar. To obviate the above difficulty a horizontally disposed platform 3 is provided on which platform the discharge end 4 of the chute 2 rests between side boards 5, which boards prevent the coal as it leaves 75 the lower end 4 of the chute from side movement, also form means for cooperating with the sides of the chute 2 for preventing lateral movement of the platform and at the same time form means for guiding the coal as it 80 moves by gravity and momentum into engagement with the horizontally disposed segmentally shaped deflecting plate 6, which plate is diagonally disposed on the platform 3 and has its ends detachably connected by 85 means of bolts 7 to the platform, which bolts pass through sleeves 7^a carried by the ends of the plate 6. It will be seen that as the coal 90 engages the segmentally shaped plate 6 that it will be deflected in the direction of the arrow *a* and discharged to one side of the platform 3 and to one side of the chute 2. The outer bolt 7 passes through one of the 95 apertures 8 in one of the corners of the platform 3 and has threaded thereon a butterfly nut 9, thereby allowing the bolt to be easily removed when it is desired to position the deflecting plate 6 in the reverse position as shown in Figure 2 for discharging the coal to the opposite side of the platform 3 in the 100 direction of the arrow *b*. The inner bolt 7 passes through apertures 10 in cleats 11 carried by the platform 3 and are provided with butterfly nuts 12 by means of which butterfly 105 nuts the bolts 7 and consequently the deflecting plates 6 will be securely held in place. It will be seen that a segmentally shaped deflecting plate 6 may be easily and quickly reversed when desired to change the direction of discharge of the coal, and that the 110 coal may be properly deflected in such a manner that it will not pile in front of the chute

and may be so deflected that it will be properly stored.

Extending rearwardly from the platform 3 are bars 13, which bars are secured at 14 to a transversely disposed bar 15. The bar 15 is provided with upwardly extending lugs 16, which lugs have pivoted at 17 there-to vertically disposed bars 18, which are in parallel relation to each other, and which in connection with the braces 19 form a substantially vertically disposed frame 20. Pivotally connected to the platform 3 at 21 is an upwardly and rearwardly extending arm 22, which arm is a brace arm and is provided with teeth 23, between which teeth a tooth 24 carried in an aperture 25 in one of the vertically disposed bars 18 is received and the bars 22 locked by a pivoted latch 26. It will be seen that by adjusting the toothed bar 22 that the platform 3 may be placed in various angled positions by the adjustment of said toothed bar and held therein. Also that the frame 20 will be held rigidly against movement on its pivotal points 17.

After the frame 20 has been properly positioned and the platform 3 properly positioned in relation to the frame 20, the upper ends 26 are disposed on each side of the chute 2 and then the hooks 27 of the blocks 28 hooked over the sides 2^a of the chute 2. The cables 29 carried by said blocks extend from their securing point 30 to the blocks, thence downwardly through eyes 31 carried by the lugs 16. It will be seen that when a pull is imparted on the portions 32 of the cables that the frame as a whole will be forced upwardly until the chain 33 which is provided with slack and has its ends connected at 34 to the upper ends of the vertical bars 18 will be forced into engagement with the under face of the chute 2, which will securely hold the frame in engagement with the chute and against movement and the platform 3 in close engagement with the discharge end 4 of the chute. If so desired the cables may have their portions 32 secured to cleats 35 carried by the platform 3. It will be seen that the hooks 27 carried by the blocks 28 are so positioned that pressure may be so applied to the chute 2 at points between the engaging point of the chain 33 with the under side of the chute and the engagement of the platform 3 with the underside of the discharge end 4 of the chute, that the attachment may be rigidly connected to the chute and suspended therefrom. However, it is to be understood that the device as a whole may rest upon the floor of the cellar if so desired.

From the above it will be seen that a coal chute attachment is provided which may be easily and quickly applied to a coal chute, and one wherein it will be possible to deflect the coal to either side of the chute for

proper distribution of the coal within the 65 cellar.

The invention having been set forth what is claimed as new and useful is:—

1. The combination with a coal chute, of a horizontally disposed platform attached to the coal chute adjacent its discharge end, a segmentally shaped horizontally disposed plate carried by the platform forwardly of the chute and detachably connected thereto, said detachable means allowing said segmentally shaped plate to be detached from the platform and positioned diagonally on the platform in front of the discharge end of the chute.

2. The combination with a coal chute, of a horizontally disposed platform detachably connected to said chute, means carried by said platform forwardly of the chute whereby coal may be deflected to either side of the platform, and upwardly extending members carried by the platform adjacent the discharge end of the chute and forming means for preventing lateral displacement of the platform and guiding discharged coal into engagement with the deflecting means.

3. A coal deflector for inclined chutes, said deflector comprising a horizontally disposed platform engaging the discharge end of the chute, means carried by said platform forwardly of the discharge end of the chute whereby coal may be discharged to either side of the chute, the rear end of said platform being pivotally mounted to a vertically disposed frame formed from spaced bars connected together, said bars being provided with a cradle for the chute formed from a slackened chain, an adjustable brace member pivoted to the platform and provided with teeth cooperating with a tooth in one of the bars of the frame and block 105 and falls connected to the rear end of the platform and to the chute and forming means whereby the platform and frame will be securely held on the chute.

4. A deflecting attachment for inclined coal chutes, said attachment comprising a horizontally disposed platform, the forward end of said platform extending forwardly of the discharge end of the chute, a horizontally disposed segmentally shaped deflecting plate diagonally disposed on the platform forwardly of the chute, and means carried by said platform and by said deflecting plate whereby said deflecting plate may be positioned in reversed diagonal position on the platform, said means comprising vertically disposed bolts carried by the platform and vertically disposed sleeves carried by the ends of the deflecting plate.

In testimony whereof I hereunto affix my signature.

HENRY ED DOWNER.
